CLAIM

The ornamental design for belt clip tool holder, substantially as shown and described.

DESCRIPTION

FIG. 1 is a front, bottom and right side perspective view of belt clip tool holder, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dominant feature of my design resides in the tool clip device fixed on the waist belt, which is convenient for the user to safely store the tool in the belt clip tool holder, so that the user can take the item more quickly, as shown.
